UNITED STATES PATENT OFFICE.

EDWARD J. FROST, OF PHILADELPHIA, PENNSYLVANIA.

APPARATUS FOR PRODUCING ILLUMINATING GAS OR VAPOR.

SPECIFICATION forming part of Letters Patent No. 278,529, dated May 29, 1883.

Application filed July 14, 1882. (No model.)

To all whom it may concern:

Be it known that I, EDWARD J. FROST, of the city and county of Philadelphia, in the State of Pennsylvania, have invented certain new and useful Improvements in Apparatus for Producing Illuminating Gas or Vapor, commonly known as "carburetors."

The following is a specification of my improvements, reference being had to the accompanying drawings, in which—

Figure 1 is a vertical longitudinal section through the center of the carburetor, showing also the feed, air-inlet, and exit pipes, partly in section and partly in elevation. Fig. 2 is a horizontal section through the carburetor on the irregular line $y-y$ of Fig. 1.

My improvements belong to that class of carburetors in which the air-current is compelled to travel through a continuous and uniform passage, usually of spiral form, in which course it takes up a volatile hydrocarbon from the surface of capillary material. In Letters Patent of the United States No. 238,020, granted to Samuel J. Anthony jointly with myself, such a carburetor is specified, the walls themselves of the spiral passage being formed of the capillary material, and the arrangement being such as to isolate the air-passage from the body of liquid which directly supplied it.

This last feature is highly desirable; and it is one of the objects of my present invention to still further insure the isolation of the air-current from any free or unsuspended liquid, and to reduce to a minimum the actual amount of free liquid in the apparatus.

My invention has for its further object the establishment of an automatic feed, which, while only admitting the minimum amount of liquid to the capillary material, shall render such supply constant.

To these ends my invention consists, primarily, in forming the carburetor with a spiral air-passage provided throughout uniform short intervals with strands of capillary material, whose ends alone are immersed in the liquid to be evaporated, the air-passage being entirely isolated from the said liquid.

My invention also consists in combining with the carbureting device of the character just indicated a tight supply-reservoir and a pipe leading therefrom to the isolated feed-cham-

ber, into which ends of the capillary material extend, the orifice of such pipe being below the diaphragm which separates the feed-chamber from the evaporating-chamber.

In Fig. 1, A represents the reservoir for the volatile liquid to be evaporated, preferably the hydrocarbon known as "gasoline." This reservoir is air-tight, and communicates by a pipe, B, controlled by a cock, b, with the closed tank D, the orifice of the pipe being preferably a very short distance—say from one-fourth to one-half inch—above the bottom of the tank. Within the tank D is the evaporating-chamber, which consists of top and bottom plates, L E, respectively, which form close joints with the spirally-coiled sheet C. The bottom plate, E, which forms the separating-diaphragm between the evaporating-chamber and the feed-chamber, is situated, as shown, above the orifice of the pipe B. The spiral sheet C may be constructed of wood veneering, as described in the patent previously referred to, or of any suitable rigid material, the arrangement, however, being such as to leave a practically continuous and uniform air-passage. At short intervals throughout the line of the spiral passage holes d are formed in the top and bottom plates, and strands e, of capillary material, preferably lamp-wicking, are drawn through these holes and across the entire depth of the chamber, the free ends of the strands extending into the space between the plate E and the bottom of the tank D. The holes d in the bottom plate are of such size as to be tightly closed by the wicking, so that no liquid can enter the evaporating-chamber except such as is drawn up by the capillary action. At the center of the tank D is the air-inlet pipe M, controlled by the cock h, and having a nozzle, j, which extends within the evaporating-chamber, while near the periphery of the tank, and adjacent to the open outer end of the spiral air-passage, is the exit-pipe R. The exit-pipe R is provided with an enlarged chamber, m, which communicates with the air-inlet pipe M by a branch pipe, O, having a regulating-cock, n. The nozzle f of the pipe R extends within the chamber m, opposite to the discharging-pipe N, which also extends within the chamber m. The nozzle f is tapered or beveled on its outside, and the closely-approxi-

mating end of the discharging-pipe N is countersunk on its interior, as shown. A blast apparatus of any suitable character communicates with the inlet-pipe M, while the discharge-pipe N is connected with the burners.

The operation of the apparatus is as follows: The liquid flows from the reservoir A into the bottom of the tank D until the level reaches the end of the pipe B, when, as the reservoir and its pipe are air-tight, no more can escape until the capillary action of the wicking takes up the liquid, thus tending to lower the level. The feed thus maintains itself automatically until the wicking is all charged, and as the level of the liquid is below the bottom plate, E, no free liquid can enter the evaporating-chamber. Moreover, the holes d are closed, by the tightly-fitting strands, against any accidental entrance of liquid due to agitation or otherwise. The blast being then turned on, the air-current traverses the spiral passage and is compelled to pass in close contact with each of the charged strands e, so that it is saturated with the vapor, after which it is discharged at the exit-pipe R. If the vapor is too rich, (as is frequently the case for some time after the commencement of the operation,) the cock n is opened and the air-blast rushes into the mixing-chamber m, where it is deflected by the tapered end of the nozzle f and the countersunk opening of the pipe N in the direction of the issuing vapor-blast, thus diluting it by the admixture of air. While this regulation is valuable in connection with the described mode of working the apparatus, it is specially so when another method of use is employed, for which the carburetor is, by reason of its peculiar construction, adapted. The great length of the air-passage and the capacity for very close and uniform arrangement of the strands affords a mass of capillary material which, in proportion to the bulk of the apparatus, is comparatively very great, and thus a large amount of liquid can be held in suspension. For example, I have arranged in a chamber of two feet diameter two thousand wicks, each composed of twelve strands of ball wicking nine and one-half inches long, and by thoroughly saturating these have succeeded in supplying six three-foot burners continuously for twenty hours after cutting off all feed. This capacity of the apparatus for running so long a time without any feed is of great value, since it not only has the advantages of a "dry carburetor," due to the isolation of the air-passage, as explained in the previous patent referred to, but dispenses with the necessity of any reservoir of liquid, either within the machine or in its vicinity, and thus avoids the danger which always attends the presence of those liquids in a free or unsuspended form.

In cars or upon vessels where the carburetor

is exposed to agitation my improved apparatus can be used with entire safety, and, moreover, the irregularity in the light which would otherwise be occasioned by the splashing about of the liquid is entirely obviated.

A little care in the adjustment of the cock n will enable the operator to preserve practical uniformity in the saturation of the vapor; but I also contemplate the use in this connection of an automatic regulator, which will form the subject of a separate application.

I am aware that it is not new to use a spiral chamber in connection with capillary material suspended therein; but so far as I am aware, in such cases, the air-passage has not been isolated from the free liquid which supplied the capillary material.

For reasons above explained this system differs radically from the feature of my invention which forms the subject of the first claim hereinafter made, and I therefore disclaim such former devices.

It is obvious, moreover, that the exact form of the air-passage above described need not be used, and although I deem a regular and uniform spiral best adapted to the desired result, I do not limit my claim to the precise form shown, provided a practically uniform and continuous air-passage be formed of closely-approximating surfaces.

I claim as new and desire to secure by Letters Patent—

1. The combination, with an inclosing tank or vessel, of a sheet of rigid material so disposed within said tank as to form a continuous and uniform air-passage with closely-approximating walls, a feed-chamber isolated from said passage, and a series of strands of capillary material regularly disposed throughout said air-passage, and forming tight joints between it and the said feed-chamber, into which they extend, substantially as set forth.

2. The combination of the evaporating-chamber, the subjacent feed-chamber isolated therefrom, the capillary material extending from said evaporating-chamber into said feed-chamber, and the air-tight oil-reservoir communicating with the feed-chamber by a pipe whose discharging-orifice is below the bottom of the evaporating-chamber, but above the ends of the capillary material, the whole operating substantially as set forth.

3. The combination, with the inclosing-tank having inlet and exit pipes for air and gas, respectively, of the spiral sheet C, the perforated plates L E, and the strands e, fitting tightly in said perforations, substantially as set forth.

EDWARD J. FROST.
